DESIGN FOR A DOLL

Anna Roosevelt Dall, Washington, D. C.

Application March 3, 1934, Serial No. 50,931

Term of patent 7 years

To all whom it may concern:

Be it known that I, ANNA ROOSEVELT DALL, a citizen of the United States, and a resident of Washington, District of Columbia, have invented a new, original, and ornamental Design for a Doll, of which the following is a specification.

Reference is had to the accompanying drawing, in which—

I claim:

The ornamental design for a doll substantially as shown.

ANNA ROOSEVELT DALL.
